UNITED STATES PATENT OFFICE.

HERMAN DOCK, OF PHILADELPHIA, PENNSYLVANIA.

DESIGN FOR AN ILLUMINATED TOY.

SPECIFICATION forming part of Design No. 26,081, dated September 22, 1896.

Application filed June 26, 1896. Serial No. 597,090. Term of patent 14 years.

To all whom it may concern:

Be it known that I, HERMAN DOCK, a citizen of the United States, residing in the city and county of Philadelphia, and State of Pennsylvania, have invented and produced a new and original Design for Toy and Advertising Display Lamps, of which the following is a specification, reference being had to the accompanying drawings, forming a part thereof.

5 In the drawings, Figure 1 is an elevation of a lamp embodying my design. Fig. 2 is a top view thereof.

10 The essential feature of my design consists in a display-lamp having the shape and appearance of a light-house of the configuration herein shown, which is provided with a lens showing a picture in the top of the gallery.

15

By reference to the drawings it will be seen that the round pillar A has a gallery B, surrounded by a circular top C, having a lens 20 D, through which a picture E is displayed, the said pillar being supported by a circular base F and the top C being capped with a hood G.

What I claim is—
25 The design for a display-lamp substantially as herein shown and described.

HERMAN DOCK.
